UNITED STATES PATENT OFFICE.

AUGUSTUS R. MCNEILL, OF OLDFIELDS, WEST VIRGINIA.

CUT-OUT.

SPECIFICATION forming part of Letters Patent No. 600,593, dated March 15, 1898.

Application filed October 7, 1897. Serial No. 654,448. (No model.)

To all whom it may concern:

Be it known that I, AUGUSTUS R. MCNEILL, a citizen of the United States, residing at Oldfields, in the county of Hardy and State of 5 West Virginia, have invented certain new and useful Improvements in Cut-Outs, of which the following is a specification.

My present invention relates to improvements in cut-outs for telephone and telegraph 10 circuits, and is fully illustrated in the accompanying drawings, in which—

Figures 1 and 2 are perspective views of the device, showing the parts in a different relation; Fig. 3, a side elevation of the device, 15 showing the means employed for making and breaking the circuit; and Fig. 4, a detail view of one of the connections.

The object of my invention is to provide 20 means whereby any single instrument may be cut out at the pleasure of the owner thereof and the main line closed, so that the circuit may not be broken or interrupted.

The invention is designed particularly for 25 use in connection with telephone-circuits such as are used in country stations and where it is often desirable to cut out a particular instrument when a local storm is in progress.

In the drawings, A denotes a post carrying 30 at its upper end a cross-bar B, upon which bar are mounted two insulators C and D. The incoming branch of the main circuit (indicated by the letter E) is connected to the insulator C and terminates in a contact-piece F. The outgoing branch of the main circuit (denoted 35 by the letter G) is connected to the insulator D and terminates in a contact-piece H. A second cross-bar I is secured upon the post at right angles to the cross-bar B and carries at its ends pivoted arms J and K. Each of the 40 arms J and K is provided with a counter-weight L, which normally tends to hold said bar in an upright or vertical position. At the inner end of each of the arms J and K, I provide a cross-bar M, to which are attached suitable contact-pieces N, N', N², and N³. 45 Contact-pieces N and N' are directly connected by a wire O. The contact-pieces N² and N³, carried upon the opposite member K, are connected with the incoming and outgoing wires P and Q, which are in circuit with the instrument placed within the house.

To bring one or the other of the arms J or

K down into a horizontal position and thereby bringing the contacts into connection, I employ a device such as shown in detail in 55 Fig. 3. To the inner end of each of the bars J and K there is connected a cord or rope R, which passes over pulleys S, T, and U, the pulleys U being placed at a point convenient to a window or door, so that the handles V, connected to the ropes or cords R by a spring W, may be conveniently reached. The cords, as will be seen, pass down through a plate X, which limits the upward movement of the spring, while a plate Y, provided 60 with notched projections, is secured below said plate X at such a point that when the handle V is engaged with one of the notches it will pull down one of the arms J or K, as the case may be, and hold the same in such 65 position that the circuit is completed through its contacts. The spring W will serve to keep the contacts in close relation with each other, and no matter whether the cord be a metallic one or one liable to elongation or 70 shrinkage from moisture the contacts will always be kept in such close relation that the circuit will not be interrupted.

With the parts in the relation shown in Fig. 75 1 the local instrument is cut out and the main line completed through the contacts F and N, line O, and contacts N' and H to the outgoing branch G of the main line. With the parts in the relation shown in Fig. 2 the instrument is in circuit with the main line—80 85 that is, the current passes in from the line E, through contacts F and N², through branch P, through the instrument, out through the branch Q, through contacts N³ and H, and on to the main line G.

Upon reference to Fig. 4 it will be seen that 90 the lower contacts carried by the cross-bar B are of a frusto-conical form, while the upper contact-pieces carried by the cross-bars are hollow and designed to fit down over the lower 95 contacts, effectually preventing any foreign substance from entering in between the two surfaces and thus impairing the continuity of the circuit.

While I have shown this form of contact 100 and have found the same to be successful in practical use, I do not desire to limit myself to this exact form, nor do I wish to be understood as limiting myself to the precise ar-

angement of the cords or cables R used for drawing down one or the other of the bars or arms J and K.

Having thus described my invention, what I claim is—

1. In a cut-out, the combination of an interrupted main line; a support; a single pair of contacts for the terminals of the main line carried by said support; a short line carried by an arm and normally out of contact with the main line; a local line carried by a second arm, also normally out of circuit with the main line; and means for moving either arm and bringing either of the lines into circuit with the main-line terminals.

2. In a cut-out, the combination of an interrupted main line; a support; a single pair of contacts for the terminals of the main line carried by said support; two arms pivoted to the support and normally held out of operative relation with the main-line contacts; a short line carried by one of the arms; a local circuit connected to the other; and means for bringing either arm down and establishing connections with the main-line terminals through the short line or through the local circuit.

3. In a cut-out, the combination of an interrupted main line; a support; a single pair of contacts for the terminals of the main line carried by said support; two arms pivoted to the support and normally held out of operative relation with the main-line contacts; a short line carried by one of said arms; a local circuit connected to the other arm; and cords connected to the arms and extending down from the support for drawing one or the other of the arms into contact with the terminals of the main line.

4. In a cut-out, the combination of an interrupted main line; a support; a single pair of contacts for the main-line terminals car-

ried by said support; two arms pivoted to the support and normally held out of operative relation with the main-line contacts; a short line carried by one of the arms; a local circuit connected to the other arm; cords connected to the arms and extending down from the support for drawing one or the other of the arms into contact with the terminals of the main line; and springs connected to the ends of the cords, substantially as and for the purpose described.

5. In a cut-out, the combination of an interrupted main line; a support; contacts for the terminals of the main line carried by the support; weighted arms J and K, pivoted to the support; contacts N, N' and circuit O carried by arm J; contacts N² and N³ carried by arm K, and a local circuit connected with said contacts; cords connected to the inner ends of the arms extending down the support to a convenient point for manipulation by the operator; and springs connected to the ends of the cords, substantially as described.

6. In a cut-out, the combination of an interrupted main line; a support B; contacts F, H, connected to the terminals of the main line; cross-bar I; counterweighted arms J, K, pivoted to said cross-bar; arms M carried at the ends of the arms J, K; contacts N, N' and circuit O; contacts N² and N³ connected with a local circuit; cords R connected to the inner ends of arms J and K and extending down the support to a point convenient for manipulation by the operator; and springs connected to the ends of the cords.

In witness whereof I hereunto set my hand in the presence of two witnesses.

AUGUSTUS R. MCNEILL.
